TARGET APPARATUS

Asa D. Hamilton, Niles, Mich.

Application October 28, 1937, Serial No. 171,421

8 Claims. (Cl. 273—102.1)

This invention relates to targets and the like, and is illustrated as embodied in an apparatus for use by two marksmen in competition with each other.

Objects of the invention are to provide a simple and effective apparatus giving an indication, preferably visual, of the accuracy of the shots, and to arrange the apparatus, according to a very important feature of the invention, to give an indication of the relative effectiveness of the firing by two marksmen.

In one desirable arrangement the indicator is controlled by shots entering a target opening, or otherwise checked as being accurate; preferably the opening is aligned with impact-operated means which operates the indicator. If the competitive feature of the invention is to be utilized, there may be two of these target openings arranged side by side and aligned in a novel manner respectively with two devices acting on the same indicator, one acting to shift it in one direction and the other acting to shift it in the opposite direction. Thus the indicator shows a resultant which shows the superior effectiveness of the firing by the better marksman.

The devices which are operated by the firing to actuate the indicator embody substantial novelty both in construction and arrangement, and especially in the manner in which they act on the indicator. They are illustrated as each operated by the impact of successful shots, to shift in one sense or the other what may be regarded as being generically a novel sort of ratchet mechanism, arranged to hold the indicator in various positions determined by the preponderance of successful shots by one marksman over the other. Preferably when it reaches one or the other of its two extremes it locks there, showing which marksman has won.

The above and other objects and features of the invention, including the construction and arrangement of the novel ratchet mechanism for operating the indicator, and an arrangement for a remote control operable from the marksmen's position for returning the indicator to zero, and other novel arrangements and desirable particular constructions, will be apparent from the following description of the illustrative embodiment shown in the accompanying drawing, in which:

Figure 1 is a rear elevation of the apparatus;

Figure 2 is a top plan view, having the casing partly broken away to show the operating mechanism within;

Figure 3 is an end elevation showing the operating mechanism;

Figure 4 is a detail elevation on a large scale of part of the ratchet mechanism appearing in Figure 1; and

Figure 5 is a partial vertical section through the ratchet mechanism.

The illustrated apparatus is intended for use as a target for two marksmen shooting competitively. It includes a suitable open-ended 10 casing 10, of boiler plate or other material which will not be injured by stray bullets, and which is secured together in any desired manner. The front panel of the casing carries, arranged side by side, two parts such as removable bushings 12 and 14, secured to the panel by locknuts 16 threaded thereon, and which have horizontal central axial openings therethrough which serve as bullseyes or target openings which the marksmen try to hit. The bushings 12 and 14 may readily be removed, for replacement with other interchangeable bushings having target openings of different sizes.

The base of the casing is shown extended rearwardly and formed with an upstanding flange 18, 25 to which is pivoted a vertically upstanding indicator arm 20 whose position indicates the relative effectiveness of the firing of the two marksmen. The casing 10 has an upstanding screen 22 (provided with a suitable scale for the indicator 20 if desired), above which projects an indicator pointer 24 connected to the indicator 20 by means such as a coil spring 26, and which is inclined rearwardly, so that if hit by a stray bullet the blow will be a glancing, yielding one and will not injure the indicator. The arm 20 may also carry suitable stops 28 limiting movement of the pointer 24. The casing is also provided with suitable brackets supporting the various parts described below.

Bullets passing through the opening in the bushing 12 impact against a steel plate 30 on an arm 32 secured on a transverse horizontal shaft 34 journaled in openings or bearings in two brackets 36 carried by the casing 10. Movement of arm 42 is limited by a suitable stationary stop bracket 37. The plate 30 is flanged around the end of the bushing 12, to limit any splashing of the lead of the bullet. Similarly bullets passing through the bushing 14 impact against a flanged plate 40 on an arm 42 secured on a shaft 44 journaled in openings or bearings carried by the brackets 36. Thus successful shots cause the rocking of one or the other of the shafts 34 and 44.

Each of the shafts has its ends bent rearwardly to form a pair of horizontal arms or operating levers, shaft 34 having arms 38 and shaft 44 having arms 48. The arms 38 pass through openings 5 in, and carry suspended therefrom, a U-shaped ratchet bar 50 (best shown in Figure 1), while the arms 48 carry a similar but somewhat longer bar 52 spaced forwardly of and parallel to and on the same level as the bar 50. The shafts 34 and 10 44 are of different lengths, so that they are also on the same level.

It will be seen that the impact of a bullet passing through one of the bushings 12 or 14 will act through arm 32 or 42 and shaft 34 or 44 to lift 15 one or the other of the ratchet bars 50 or 52. These bars, in their central portions, are formed with oppositely-directed ratchet teeth 54 (see Figure 4) engaging, when the corresponding bar 50 or 52 is so raised, one end or the other of an 20 axle 56 (Figure 5) fixed in a ratchet roller 58 normally resting in the recesses between teeth on the upper edge of a stationary horizontal ratchet bar 60.

The roller 58 is shown with flanges 62 embracing the bar 60 between them; these flanges are also shown embracing a stationary stop bar 64 above and paralleling the ratchet bar 60, and which limits upward movement of the roller 58.

The axle 56 is shown as carrying, suspended from its ends, a yoke 66 having pivotally mounted 30 at its lower end a grooved roller 68 the upper edge of which engages a horizontal but vertically-bowed coil spring 70 tensioned across the casting 10.

It will be seen that spring 70 is additionally tensioned by lifting either of the ratchet bars 50 or 52, and that it therefore serves as a return spring for all of the parts attached to the shafts 34 and 44. However, the ratchet bars may also have return springs 71 and 72 connected to their 40 ends, if desired. Normally spring 70 holds the roller 58 yieldingly against the bar 60 in one of the spaces between the teeth on its upper edge, as shown in Figure 4, with two of the teeth on the bars 50 and 52 just below and extending just 45 past, in opposite directions, the ends of the axle 56.

From the foregoing description, it will be apparent that the impact of a bullet on the plate 50 40, for example, will lift the bar 52 causing one of the teeth on the bar to lift the roller off the bar 60 against the resistance of the spring 70, whereupon the axle 56 will roll down the tooth which so engages it (to the left in Figure 4) so that when the parts swing back to normal the 55 roller 56 seats in the next recess to the left between the teeth on bar 60. A bullet engaging the plate 30 will similarly shift the roller 58 one tooth to the right in Figure 4.

The rear strap of the yoke 66 carries a slotted 60 plate 74, or equivalent means, embracing the indicator arm 20, so the shifting of the roller 58 correspondingly shifts the indicator.

The teeth on the bar 60 define several positions 65 76, 78, 80, 82, etc., of the indicator, at the right and left of its central or zero position. I prefer to form the teeth on the bars 50 and 52, at the ends of the bars toward which they shift the roller 58, with slopes in both directions, instead of a slope on the operating side and a 70 vertical surface on the other side. Thus at either extreme position 84 or 86 the indicator becomes, in effect, locked in place, so that it is not shifted either way by further "hits."

At the end of each round of firing the indicator 75 may be returned to zero by a remote control op-

erable from the marksmen's position. The particular control illustrated is a cord or cable 88, passing over a pulley 90, and connected to a vertical lever 92 fulcrumed on a bracket 94. The lever 92 is connected at its upper end to a return spring 96, which normally holds it against a stop on the bracket 94.

Connected to the lever 92 is a cord 98 passing between a pair of sheaves 100 and connected to the axle 56. This cord is long enough so that it 10 does not interfere with the shifting of the indicator to either position 84 or 86; however, when the lever 92 is rocked the cord 98 pulls the indicator mechanism back from either extreme to the zero position.

From Figure 3 it will be apparent that I prefer to arrange the shafts 34 and 44 considerably above the level of the bushings 12 and 14, with the levers 32 and 42 inclined downwardly therefrom, so that plates 30 and 40 are correspondingly 20 inclined and engage the beveled rear ends of the bushings 12 and 14. This prevents possible damage from direct impact by the bullets, as it insures a glancing blow.

While I have described in detail one embodiment of my invention, in which the impact of the bullets actuates the indicator, it is not my intention to limit the scope of the invention to that particular embodiment, or otherwise than by the terms of the appended claims.

I claim:

1. Target apparatus comprising an indicator having positions on opposite sides of a neutral center, impact-actuated devices for shifting the indicator progressively along said positions, said devices acting to shift the indicator in opposite directions, means for holding the indicator in either extreme position whenever it reaches that position, and means operable from a remote point for returning the indicator to said neutral center.

2. Target apparatus comprising a pair of impact-actuated devices arranged side by side, parts having target openings aligned with and affording access of bullets to said devices to actuate them, and indicator means actuated in one sense by one of said devices and in the other sense by the other of said devices, said means including a member shiftable to different positions on opposite sides of a zero position, and means for locking it in either of two extreme positions.

3. Target apparatus comprising a plurality of devices actuated under the control of accurate shots by a corresponding plurality of marksmen, and indicator means operated jointly by said devices and shifted to one or the other of a plurality of final positions by a predetermined preponderance of accurate shots by one of the marksmen, in combination with means for holding the indicator means in said final positions.

4. Target apparatus comprising a plurality of devices actuated under the control of accurate shots by a corresponding plurality of marksmen, and indicator means operated jointly by said devices and shifted to one or the other of a plurality of final positions by a predetermined 65 preponderance of accurate shots by one of the marksmen, in combination with means for holding the indicator means in said final positions, and means for returning the indicator means to its initial position.

5. Apparatus of the class described comprising two actuating devices arranged operatively in line with target openings, a ratchet bar, a member shifted in one direction along said bar by one of said devices and shifted in the other direction 75

along said bar by the other of said devices, and indicating means actuated by said member.

6. Apparatus of the class described comprising two actuating devices arranged side by side operatively in line with target openings, a transverse ratchet bar, a member shifted in one direction along said bar by one of said devices and shifted in the other direction along said bar by the other of said devices, and a vertical indicating arm actuated by said member.

7. An actuator mechanism for apparatus of the class described comprising a horizontal bar formed with ratchet teeth on its upper edge, a roller resting on said teeth and having flanges 10 embracing said bar, an upper horizontal bar

spaced above the roller and embraced between the flanges, devices for shifting the roller in opposite directions from one tooth to the next of said bar, and marksmen-controlled means for operating said devices.

8. Target apparatus comprising a casing formed with a target opening, an actuating device in the casing in line with said opening, a ratchet bar, a member shiftable in step-by-step movement along said ratchet bar, a movable bar having sloping teeth engageable with said member to shift it along the ratchet bar, and means operated by said actuating device to move said movable bar thereby to shift said member.
